CRUSHER

Edward H. Frickey, Pasadena Park, Mo.

Application May 22, 1931. Serial No. 539,178

2 Claims. (Cl. 83—11)

This invention relates to crushers, and with regard to more specific features to crushers for material such as limestone, shale, iron ore, coal, gypsum, asphalt rock and similar materials which 5 may contain moist impurities such as clay or mud.

Among the several objects of the invention may be known the provision of a crusher which is adapted to handle material to be crushed which has a relatively large amount of foreign matter 10 therewith, such as mud and the like; the provision of a crusher of the class described which is adapted to mechanically separate detrimental clogging material from the desired product, and which is adapted to continuously carry off said 15 separated clogging material; and, the provision of a crusher of the class described which is simple to operate, and completely enclosed. Other objects will be in part obvious and in part pointed out hereinafter.

20 The invention accordingly comprises the elements and combinations of elements, features of construction, and arrangements of parts which will be exemplified in the structure hereinafter described, and the scope of the application of 25 which will be indicated in the following claims.

In the accompanying drawings, in which is illustrated one of various possible embodiments of the invention,

Fig. 1 is a right side elevation of the crusher, 30 certain parts being broken away;

Fig. 2 is a rear elevation of the crusher shown in Fig. 1;

Fig. 3 is a vertical section taken on line 3—3 of Fig. 1; and,

35 Fig. 4 is a plan view of a pair of joined links.

Similar reference characters indicate corresponding parts throughout the several views of the drawings.

Referring now to the drawings, and more particularly to the crusher per se, there is illustrated a frame comprised of side castings 13 and having a hopper chute 7. The two side castings 13 are suitably braced and held apart by end castings, said castings 13 being bolted thereto by 40 bolts 12. The castings 13 are an assembly of component castings and serve to close part of the device and to also tie the ends of castings together at their upper portions. Thus, the side castings 13 and the end castings comprise a frame 45

50 3 adapted to enclose a set of rotary hammers 19 mounted between discs 17 (Fig. 3). The disc faces are machined to receive the hammers between them and are provided with through bolts 21 for tightening the hammers. Other holes 23 55 in the discs permit adjustment of each set of

hammers as wear on said hammers takes place. The adjustment is radial so that as the hammers wear shorter, compensation may be effected.

The discs and hammers are mounted upon a shaft 25 running cross-wise of the machine. This 60 shaft is borne in ring-oiled bearings 27 at each side of the device. The bearings are cast with the side castings. On the left end of the shaft, and outside of the machine is borne a fly-wheel 29, and on its right end a driving coupling 31. 65

Cradled below the rotary hammers 17 are cage bars 33. They are held in position by means of bolts 35 and cage liners 37. The liners are bolted to the side castings 13 and serve as end supports for the cage bars. They also protect the 70 surfaces to which they are bolted from abrasion. These bars serve to permit only material which has been crushed down to a proper size to pass out of the base of the machine.

At the ends of the hammer-disc assembly, or 75 rotor, are placed end liners 39. These are bolted to the frame 3 and serve as renewable safeguards against abrasion of said parts. The chute 7 is lined with liners 14 at points subjected to abrasion.

80 Forwardly of said machine a shaft 45 running crosswise of the machine is mounted in adjustable bearings 47. The bearings are fastened to the upper ends of bearing supports 49 which are suitably fastened to the side of the frame 3. Set 85 screws 53 are adapted to adjust the bearings 47 in the bearing supports 49. The shaft 45 carries sprockets 55 which are adapted to carry an anchor plate chain 61 to be carried thereon.

85 A shaft 57, similar to the shaft 45, mounted between the end castings and supported thereby carries sprockets 59 similar to sprockets 55. Over the sprockets 55 and 59 is placed said belt or chain 61 comprising links or breaker plates 62 formed of manganese steel or other wear or impact resisting material. Each link 62 comprises a bar at the ends and on one side of which are formed oppositely jutting gudgeons 64 adapted to ride between the teeth of the sprockets 55 and 57 and to be driven thereby. These gudgeons are 90 properly rounded to kinematically mesh with proper teeth on the sprockets. On one edge of each of the links 62 are formed projections or hinged portions 66. On the other edge are formed similar projections 63 in staggered relationship to the portions 66 thereby a series of links 62 (see Fig. 4) may be interfitted. Through the various sets of interfitting hinged portions 63 and 66 are bored, or otherwise formed, aligned holes 70 adapted to receive a link pin or rod 72. The holes 110

- 70 pass through said gudgeons 64 and are therein countersunk. The rod 72 is riveted over at the countersunk holes as the chain 61 is made and is formed flush with the gudgeons ends.
- 5 It is thus evident that the gudgeons 64 serve to mesh with the sprockets 55 and 57 and may be driven thereby, and thus the chain is driven as the sprockets are rotated, as indicated in Fig. 2, by the coupling 83.
- 10 The link chain or breaker plate 61 and the hammers 17 form the crushing elements of the crusher. The links 62 cover the width of the hammer rotor in projection. In order to withstand the attendant impact of the crushing operation, the chain 61 is backed by a suitable rugged 15 paten 63. The paten 63 is pivoted to the side castings 13 of the frame by means of a shaft 65, and backs the breaker plates at the point of impact. It may be adjusted to different required 20 degrees of slope of the breaker plates or to different degrees of wear in said hammers by means of the lateral shafts 67 passing through slots 73 in flanges 74 of the paten 63 and through slots 76 in the side castings 13. Outside of the castings 13 25 the shaft 67 is bolted at each end to side bars 69 which extend through lugs 71 of the castings. These side bars may be adjusted by means of the nuts 73 and are adapted to govern the swing position of the paten 63 about its shaft 65. The 30 auxiliary shaft 75 working in slots similar to the above-mentioned one serves to hold the paten in position by clamping its ends to said castings 13. The breaker plate train is driven relatively slowly by means of the splined universal joint 83 and the 35 shaft 25 of the hammers is driven relatively fast through a belt connection to the coupler 31. It is thus seen that the material to be crushed, is fed to the hopper 7, and by gravity and with the help of the moving breaker chain 61 is carried in and is 40 crushed by the hammers 19 against the chain 61, and is passed through the cage bars 33.
- When materials which are extremely wet and have associated with them a great deal of dirt and clay or the like, are crushed in a crusher such as 45 was hereinbefore described, the mud packs around and sticks to the cage bars 33 and interferes in general with the operation of the crusher. I have overcome this difficulty by opening the top of the crusher in order that the dirt, mud and the 50 like may be thrown out of the crusher and have provided means for continuously removing said mud and dirt as it is thrown out. Thus such a crusher may be adapted to crush mud laden material.
- 55 Referring now to the means provided for removing such mud, as shown in Fig. 3 top covers have been removed and a box like cover 84 comprising side portions 85, end portions 87 and a top piece 89 has been substituted. Thus the immediate cover for the crusher has been removed and a 60 completely enclosing but spaced cover has been substituted. The side and top pieces 85 and 87 and 89 are formed from a relatively lightweight material, inasmuch as they receive no appreciable 65 shocks. They are suitably joined together by channel pieces and L pieces 91 to provide a relatively rigid structure or box-like cover 84. The side walls 85 of the box cover 84 are bolted to the side castings 13 by bolts 93. A heavier plate 95 70 extending crosswise the width of the machine is adapted to prevent mud or crushed material from flying into the hopper 7.
- Mounted on the shaft 57, and driven thereby is a sprocket 101 adapted to drive another sprocket 103 by a chain 100. The sprocket 103 75 is keyed to and mounted on a shaft 104 on which is also mounted a sprocket 105. The sprocket 105, driven by the shaft 104, is adapted to drive another sprocket 107 by the chain 106. The sprocket 107 is keyed to a shaft 108 on which is 80 also mounted a gear 109. Shafts 117 and 119 respectively, are suitably mounted in bearings and extend crosswise inside of the box cover 84. Gears 113 and 115 mounted on the shaft 117 and 119 respectively and outside the cover 84, mesh with the teeth of the gear 109, and consequently are driven by the gear 109. A plurality of sprockets 123 and 125 are respectively mounted on the shafts 117 and 119 inside the box 84 and are adapted to drive and support chain belts 127 and 129 respectively, the chain belts being 85 similar to the breaker plate belts 61, but of much lighter weight. It is to be understood, however, that the chains 127 and 129 may comprise a plurality of individual chains mounted close together. A shaft 131, extending crosswise and inside of said box cover 84 and suitably mounted in adjustable bearings 132 is adapted to mount a plurality of sprockets 133 (Fig. 3), which 90 guide the chain 127, extending crosswise and lengthwise of said box 84. Likewise, a shaft 135 95 adjustably mounted in bearings 136 supports a plurality of sprockets 137 which guide the chain 129.
- The tension in the chains 127 and 129 is adjustable by means of the adjustable bearings 132 and 136. 100
- Thus the chains 127 and 129 are driven by the sprocket 101 mounted on the shaft 57, which shaft is driven by the splined coupler 33. The 110 movement of the chains 127 and 129, as shown by the arrows, provide respectively a moving top or ceiling for the box 84 which moves to the rear thereof, and a moving back surface of the box 84 which moves from the top to the bottom thereof, and thus material striking and sticking to any portions of the surfaces provided by the 115 chains 127 and 129 is carried away from the crusher.
- The operation of the apparatus is as follows: 120
- Mud laden material to be crushed is fed into the hopper 7 and gravity carries it downward on the sloping breaker plate chain 61, which is also moving downward, into the paths of the rapidly rotating hammers 19. These hammers impact 125 the lumpy material against the slowly moving breaker plate chains 61, thereby breaking most of the lumps of the material down to a size small enough to pass the cage bars 33. Substantially 130 all of the material is crushed before it reaches the end of the cage bar area. I have found that the wet mud and clay and other foreign materials which would otherwise tend to clog the plates 135 33 is picked up by the hammers at the mouth of the hopper 7 and from the cage bars 33 and carried around the grinder, past the cage bars 33 until at approximately the area of the grinder marked X it begins to leave the hammers and is thrown off by the action of centrifugal force. Thus by the time the hammers reach the portion 140 of the grinder marked Y the hammers are substantially free from mud. In this way, the mud which would otherwise collect over the cage bars 33 and over the top of the crusher has been removed.
- The mud material thus slung from the hammers flies out of the grinder casing proper onto the moving surfaces provided by the plate chains 127 and 129. Most of the mud striking the 145 chains 127 and 129 is dropped off at the point 150

where the chain goes around the sprockets 123 and 137 respectively but suitable means may be provided to remove the mud in the event that it is unusually sticky and does not drop off.

5 The mud thus removed drops down and may be removed in any suitable manner as for instance through a door 139 in the side of the cover 84.

Inasmuch as the wet mud substantially increases the friction between the material being 10 crushed and the cage bars, substantially all the material is crushed and passed through the cage bars 33 by the time it reaches the end of the cage bar area, and hence, very little escapes into the cover box 84. Thus substantially mud

15 only strikes the chains 127 and 129 and accordingly they may be of relatively light weight construction. Hence the initial cost of the chains 127 and 129 and the cost of the power required to run them is relatively small.

20 An advantage of the invention is that the type of grinder herein described may be used for grinding wet and mud laden materials whereas formerly much difficulty was incurred in endeavoring to grind such materials in this type of crusher. Furthermore, with my invention it is possible to substantially separate the mud from the final product and such a separation is often greatly desired. The light weight and simplified construction, as well as the type of drive used makes 25 the invention commercially attractive from a financial standpoint. It may or may not be sold separately from the regular grinders and hence other hammer crushers may be equipped with my invention to crush mud laden materials.

30 The moving surfaces 127 and 129 are adapted to prevent the mud, removed from the crusher, from piling up on the sides of the cover 84 and to provide a cheap and effective method of continuously and efficiently removing the deposit. 35 Further, the bearing adjustments available are adapted to insure adjustments for most satisfactory working conditions.

In view of the above, it will be seen that the 40 several objects of the invention are achieved and other advantageous results obtained.

45 As many changes could be made in carrying out the above constructions without departing from the scope of the invention, it is intended that all matter contained in the above description or shown in the accompanying drawings

shall be interpreted as illustrative and not in a limiting sense.

I claim:

1. In a crusher, rotary crushing hammers, means cooperating with said hammers at one tangent region to effect crushing, a crushed-material outlet associated with said hammers adjacent the crushing region, arcuately located cage bars below and adjacent to the hammers, said crusher having a foreign-material outlet 80 adjacent said hammers beyond said cage bars, the crusher having a passage joining said outlet and leading to a region separate from the region of delivery of crushed material, said foreign-material outlet being arranged to provide substantial upward movement of foreign material tangentially from the hammers, and a reach of movable conveyor means directed laterally from said foreign material outlet and located thereabove and adapted to carry centrifugally separated foreign material away from said foreign-material outlet, and a second reach of conveyor means angularly located with respect to said first reach, said reaches each comprising a separate endless chain, and clean-out means located adjacent the end of the second reach, said cleanout means being at a point separate from the point of delivery of crushed material. 90

2. In a crusher, rotary crushing hammers, means cooperating with said hammers at one region to effect crushing, a crushed-material outlet associated with said hammers adjacent the crushing region, cage bars located below said hammers, said crusher having a foreign-material outlet adjacent to said hammers and beyond said cage bars, the crusher having a passage joining said outlet leading to a region separate from the region of delivery of crushed material, said foreign-material outlet being arranged to provide substantial upward movement of foreign material tangentially from the hammers, and a reach of conveyor means directed laterally from said foreign-material outlet and located thereabove, and adapted to carry centrifugally separated foreign-material away from said foreign-material outlet, and a second reach of conveyor means angularly located with respect to said first reach and directed downwardly, said reaches each comprising separate endless chains. 100 110 115 120 125

EDWARD H. FRICKEY.
